BALLAST CONSTRUCTION

Joseph C. Yaeger, Milwaukee, Wis., assignor to McGraw-Edison Company, a corporation of Delaware

Application June 15, 1956, Serial No. 591,711

3 Claims. (Cl. 315—241)

This invention relates to a constant wattage ballast construction which is particularly useful in mercury vapor lighting systems where a separate ballast is provided for each lamp.

In mercury vapor lighting systems where the mercury vapor lamps are placed in shunt, it is a customary practice to provide each lamp with an individual constant wattage ballast. These ballasts are units which comprise in effect a transformer and condensers associated therewith, in which the transformers are usually so constructed that a magnetic shunt or magnetic leak is provided.

It has been found that when the lamp current crest factor, which is the ratio of the peak current to the R.M.S., is high that the total output of light for the life of the lamp is lower than where the crest factor is lower. While the theory is not entirely clear it is believed that this is due to the fact that the low electron affinity material with which the one or more electrodes of the mercury vapor lamp are provided seems to "boil out" or to be driven off for the high current peaks where there is a high crest factor. This material collects or condenses on the inner walls of the quartz or hard glass tube of the mercury vapor lamp, and lowers the lumen output of the lamp after a relatively short period of use so that during the entire life period of the lamp its total light output is less than where the crest factor is lower. The lower crest factor occurs when the peak or crest current is relatively low whereas, on the other hand, the peak or crest current for a high crest factor is relatively high. Consequently, for a low crest factor there is less chance of the "boiling off" or driving off of the low electron affinity material with the deleterious effects hereinabove noted.

In ballasts of the above type, it is the usual practice to provide two resonant circuits associated with the secondary or output portion of the transformer of the constant wattage ballast. It is the customary practice to so arrange the circuits that what may be called the first resonant circuit, resonates at the third harmonic and is employed to secure a high striking or starting voltage for the mercury vapor lamp. In the customary practice, what may be called the second or operating circuit is so arranged that it resonates at the fundamental frequency.

It has been found through extensive experimentation that in the usual forms of ballasts hereinabove discussed, the third harmonic is still present in an undesirably high value during the normal operation of the lamp and consequently the lamp current crest factor is high, thus limiting or lowering the entire output during the total life period of the lamp.

This invention is designed to provide a constant wattage ballast which has a low value for the third harmonic current during the operating period of the lamp, that is to say, while the lamp is hot and is operating in its normal capacity. As shown hereinabove, this reduces the amount of low electron affinity material that is driven off from an electrode of the lamp since the peak value

2

of the alternating current during operating conditions is lower due to the reduction of the third harmonic.

It has been found further that where the crest factor is high, that the warm-up period of the lamp is increased over that required where the crest factor is lower. In certain instances the lamp never fully warms up and consequently fails to function properly where the crest factor is high. It is, therefore, a further object to provide a ballast which is so constructed that the warm-up period of the mercury vapor lamp is reduced.

A specific object of this invention is to provide a ballast construction in which one of the elements of the resonant circuit which resonates at the third harmonic is in effect shorted out or partially shorted out during the operating period of the lamp, so that the value of the third harmonic current, when the lamp is in operation, is greatly reduced while at the same time the output circuit is arranged to resonate at 60 cycles.

An embodiment of the invention is shown in the accompanying drawings in which:

Figure 1 is a diagrammatic view of the constant wattage ballast.

Figure 2 is a fragmentary view of a portion of the ballast showing primarily the magnetic core and windings.

25 It is customary to construct the ballast as a unitary structure with all of the component parts carried in a housing or casing. This is diagrammatically shown in Figure 1 by the dotted line indicated by the reference character 1.

30 The transformer consists of the main core 2 of laminated material provided with magnetic shunts 3. As a matter of fact, the transformer is not made of an unbroken sheet for each lamination as indicated in Figure 2, but is made of the usual strips or punchings which are built up into the final form shown in Figure 2. The magnetic shunts are diagrammatically shown in Figure 1. The shunts may be formed as shown in Figure 2 and indicated at 3 by suitably stamping out the core 2. The primary is shown at 4 and the secondary at 5. The primary may have taps if desired, or may be formed as shown in Figure 1 of two windings which may be connected either in shunt or in parallel for 110-130 volts or 220-260 volts. The secondary supplies a single mercury vapor lamp indicated by the reference character 6. In the 35 system of mercury vapor lighting for which this ballast is made, each lamp is provided with its own individual ballast.

40 A relatively large capacitor indicated by the reference character 7 is placed in series with the secondary 5 and is shunted by a high resistance leak of the order of several hundred thousand ohms. A capacitor 9 of relatively low capacitance, as compared with the capacitor 7, is connected directly across the output leads from the secondary 5. It is to be noted particularly that the capacitor 7 is connected on the outer side or delivery side between the lamp 6 and the rest of the secondary circuit. This is a very important feature of the invention. It is connected in such a manner as shown in Figure 1 that the lamp 6 directly bridges the capacitor 9.

45 When the lamp is not in operation, that is to say, when the lamp is cold, the capacitor 9 is effective and forms a portion of a resonant circuit including the capacitor 9, the capacitor 7, and the secondary 5. This circuit resonates for the third harmonic. However, when the lamp 5 is in operation, it provides a shorting or bridging circuit directly across the capacitor 9 thereby greatly lessening the effect of the capacitor 9 or else entirely suppressing the action of the capacitor 9 so that the resonant circuit hereinabove mentioned for the third harmonic no longer exists, or if it operates at all in resonance, its effect is tremendously reduced.

50 On the other hand, when the lamp has struck and is

operating, it forms a portion of a resonant circuit including the lamp 6, the capacitor 7 and the secondary 5. This circuit resonates at the fundamental frequency. During the normal operation of the lamp the third harmonic is practically, if not entirely, suppressed as explained hereinabove.

The input and output terminals of the constant wattage ballast are indicated by the reference characters 11, 11 and 10, 10 respectively. It is to be understood that the magnetic shunts 3 operate in the usual manner to limit the current by providing a leakage path for the magnetic flux.

It will be readily seen that the crest factor is greatly reduced during operating conditions of the lamp since the third harmonic is materially reduced if not completely suppressed. In other words, the lamp 6 tends to short out the capacitor 9 and consequently to suppress the third harmonic which causes the high peaks in the alternating current wave. This suppression of the third harmonic results in the low crest factor.

It is essential that the capacitor 9 be connected at a point beyond the capacitor 7. That is to say on the side of the capacitor 7 opposite the secondary 5, as explained hereinabove.

It will be seen that a relatively simple construction is provided by this invention in which the ballast produces the minimum of the third harmonic, and consequently greatly reduces the value of the crest factor.

From actual tests it has been found that the warm-up period of the lamp is materially reduced by reducing the crest factor as hereinabove set forth.

Although this invention has been described in considerable detail, it is to be understood that such description is intended as illustrative rather than limiting, as the invention may be variously embodied and is to be interpreted as claimed.

I claim:

1. A mercury vapor alternating current lighting system for striking and operating mercury vapor lamps comprising a ballast having input and output terminals, a mercury vapor lamp connected across the output terminals, said ballast comprising a transformer having a primary connected to the input terminals and having a secondary, a relatively large capacitor connected in series between an output terminal and one side of said secondary, the other side of said secondary being connected to the other output terminal, a relatively small capacitor connected across the output terminals between the output terminals and the first mentioned capacitor and being directly bridged by said mercury vapor lamp, whereby when said mercury vapor lamp is lighted it forms a short circuit directly bridging said second mentioned capacitor, the lamp, the relatively large capacitor, and the secondary forming the major part of a circuit resonating at the fundamental frequency, and the relatively small capaci-

tor, the relatively large capacitor, and the secondary forming a circuit resonating at an odd harmonic frequency.

2. A mercury vapor alternating current lighting system for striking and operating mercury vapor lamps comprising a ballast having input and output terminals, a mercury vapor lamp connected across the output terminals, said ballast comprising a transformer having a primary connected to the input terminals and having a secondary, said transformer having magnetic shunting means provided with an air gap and located between said primary and said secondary, relatively large capacitor means connected in series between an output terminal and one side of said secondary, the other side of said secondary being connected to the other output terminal, a relatively small capacitor connected across the output terminals between the output terminals and said capacitor means and being directly bridged by said mercury vapor lamp, whereby when said mercury vapor lamp is lighted it forms a short circuit directly bridging said relatively small capacitor, the lamp, the relatively large capacitor means, and the secondary forming the major part of a circuit resonating at the fundamental frequency, and the relatively small capacitor, the relatively large capacitor means, and the secondary forming a circuit resonating at an odd harmonic frequency.

3. A mercury vapor alternating current lighting system for striking and operating mercury vapor lamps comprising a ballast having input and output terminals, a mercury vapor lamp connected across the output terminals, said ballast comprising a transformer having a primary connected to the input terminals and having a secondary, a relatively large capacitor means connected in series between the output terminals and said secondary, a relatively small capacitor connected across the output terminals between the output terminals and said capacitor means and being directly bridged by said mercury vapor lamp, whereby when said mercury vapor lamp is lighted it forms a short circuit directly bridging said relatively small capacitor, the lamp, the relatively large capacitor means, and the secondary forming the major part of a circuit resonating at the fundamental frequency, and the relatively small capacitor, the relatively large capacitor means, and the secondary forming a circuit resonating at an odd harmonic frequency.
